Application May 23, 1944, Serial No. 113,722

Term of patent 7 years

(Cl. D34—5)

To all whom it may concern:

Be it known that we, Irma S. Ellicott and Eugene W. Silber, both citizens of the United States, residing at West Orange, in the county of Essex and State of New Jersey, have invented a new, original, and ornamental Design for a Game Board, of which the following is a specification, reference being had to the accompanying drawing, forming a part thereof.

In said drawing the figure is a plan view of a game board embodying our new design, said board being flat and of conventional thickness.

We claim:

The ornamental design for a game board, as shown and described.

IRMA S. ELLICOTT.
EUGENE W. SILBER.
